UNITED STATES PATENT OFFICE.

CHARLES H. DANKMEYER, OF BALTIMORE, MARYLAND.

BELTING FABRIC.

1,347,254.

Specification of Letters Patent.

Patented July 20, 1920.

Application filed May 14, 1920. Serial No. 381,237.

To all whom it may concern:

Be it known that I, CHARLES H. DANKMEYER, a citizen of the United States of America, residing in the city of Baltimore, 5 State of Maryland, have invented certain new and useful Improvements in Belting Fabrics, of which the following is a specification.

An objectionable feature of the cotton 10 duck belting in common use is the tendency of the material to stretch, so that repeated adjustment is necessary; also, the scarcity of cotton and the advance in cost have made the discovery of a practical substitute for part 15 or all of the cotton fiber used an important consideration.

To fill a stitched cotton duck belt, by placing a piece of burlap within the layers of duck, is a fairly well known expedient, but 20 it has not been successful owing to the difference in stretch and shrinkage between the two materials, the tendency of the cotton to stretch and shrink being excessive, while the burlap, which is of hemp or jute, is almost 25 completely without elasticity or shrinkage.

The object of the present invention is to produce a cheaper belt as compared to the all-cotton product, and one which is at the same time of improved quality, in that 30 while it retains a certain amount of elasticity, which is desirable, excessive stretch is eliminated. This is accomplished by introducing into the fabric a considerable proportion of hemp or jute fiber, so arranged 35 that the difference in quality as to elasticity has no harmful effect; on the contrary, the use of the coarser and harder fiber in this way decreases the stretch, leaving only such elasticity as is beneficial and otherwise 40 results in a better and more permanent product.

To avoid the difficulties hitherto encountered due to the difference in shrinkage and stretch, I lay the cotton fibers in the direction of the length of the belt, and the 45 harder fibers transversely—*i. e.*, in weaving the material I use a cotton warp and a hemp woof, or filling. In this connection it should be understood that in the stretching of a fabric of soft fiber there is a considerable amount of give or yielding of the transverse threads as well as of the longitudinal threads, and the substitution of a harder fiber for the soft weft increases the resistance of the fabric and reduces its elasticity. 50

In the accompanying drawing I have shown a stitched fabric belting, made in accordance with my invention, the figure being a cross-section of the belting, taken on a plane transversely of the length of the 60 fabric.

Referring to the drawing by numerals, the piece of belting shown is composed of a strip of fabric 1, having a cotton warp 2, and a hemp or jute filling 3, the fabric 1 being folded upon itself to form four layers and then sewed through and through forming stitches 4, in parallel rows, extending in the direction of the length. 65

What I claim and desire to secure by Letters Patent is:

1. A belting fabric having a cotton warp and a hemp filling.
2. A solid woven belting, with cotton warp and hemp filling.

Signed by me at Baltimore, Maryland, 75 this 7th day of May, 1920.

CHARLES H. DANKMEYER.
